(57) **CLAIM**

(**) Term: **14 Years**

We claim the ornamental design for door for drum-type washing machine, as shown and described.

(21) Appl. No.: **29/353,056**

DESCRIPTION

(22) Filed: **Dec. 31, 2009**

FIG. 1 is a front/right-side/top perspective view of a door for drum-type washing machine showing our new design;

(51) **LOC (9) Cl.** **15-05**

FIG. 2 is a front-side elevational view thereof;

(52) **U.S. Cl.** **D32/25**

FIG. 3 is a rear-side elevational view thereof;

(58) **Field of Classification Search** D32/6,

FIG. 4 is a left-side elevational view thereof;

D32/8, 5, 10, 1, 9, 25; 68/3 R, 5 R, 12.01,
68/212; 34/523-524

FIG. 5 is a right-side elevational view thereof;

See application file for complete search history.

FIG. 6 is a top-side elevational view thereof; and

(56) **References Cited**

FIG. 7 is a bottom-side elevational view thereof; and,

U.S. PATENT DOCUMENTS

FIG. 8 is a front/top perspective view which shows a door for drum-type washing machine are positioned on the front panel of washing machine.
